UNITED STATES PATENT OFFICE.

JOSEPH E. ROUSSEAU AND LOUIS O. BRUNELLE, OF HAVERHILL, MASSACHUSETTS,
ASSIGNORS TO UNITED SHOE MACHINERY CORPORATION, OF PATERSON, NEW JER-
SEY, A CORPORATION OF NEW JERSEY.

WOOD-HEEL CLAMP.

Application filed December 7, 1923, Serial No. 679,080. Renewed April 22, 1928.

This invention relates to that class of devices which are employed to clamp a wood heel on the heel seat of a shoe when attaching the heel in position by means of an adhesive, to hold the heel until the adhesive sets.

Prior to our invention numerous forms of clamps for the above-mentioned purpose have been employed, but these clamps are open to various objections. For example, it has been customary to clamp the heel to the shoe by means of an ordinary iron C-clamp. Another form of clamp which has been in use for many years comprises a last-engaging member adjustably mounted on a support and a heel-top engaging member having a hand operated cam for forcing it towards the last-engaging member. These devices are objectionable because the heel once positioned, is frequently displaced while the clamping means is being operated and cannot be reset in position until the clamping means has been restored to initial inoperative position. Furthermore, such devices are not adapted satisfactorily to clamp heels of considerable variation in pitch, and it often happens that, while a heel may be clamped as tightly as possible when the clamping pressure is first applied, the heel seat will yield shortly thereafter, so that the heel will no longer be tightly clamped and as a result will be insecurely attached by the adhesive and will fall off the shoe when the shoe is removed from the clamp, or later when it is attempted to drive the attaching nails. The clamps heretofore used are also usually cumbersome and inconvenient to handle.

One object of our invention is to provide an improved clamp which will be adapted to permit a heel to be readily reset if it should become accidentally displaced or, in case it should be found that the heel has not been set initially in proper position.

With this object in view, one feature of our invention consists in the provision of means for moving a resilient clamp member in a direction heightwise of a heel on a shoe, constructed and arranged to permit a limited amount of movement of the clamp member in that direction without affecting the resiliency of the member independently of its operating means so that the clamp member may be moved into clamping position and withdrawn therefrom, if desired, with-

out any actuation of the means for applying the clamping pressure. Thus if the heel becomes displaced at any time before the clamping pressure is actually applied thereto, the heel may be reset without any loss of time or necessity of manipulating the pressure applying means.

Another object of the invention is to provide a clamp which will apply an effective and adequate clamping pressure even though the material at the heel seat or other portion of the structure clamped should yield at any time after the clamp has been adjusted in place.

To the accomplishment of this object and in accordance with another feature of the invention, the illustrated clamp member is made of resilient metal shaped and arranged so that it will yield a substantial amount under the clamping pressure. Thus, if the heel seat materials should yield after the clamp member has been moved into clamping position the clamp member will react to prevent substantial relieving of the clamping pressure.

Other objects and features of the invention will appear from the following description of the preferred embodiment thereof illustrated in the accompanying drawings, in which—

Fig. 1 is a side elevation of a wood heel clamp embodying our invention, and showing a heel in clamped position.

Fig. 2 is a rear end view, and

Fig. 3 is a top plan view thereof.

Figs. 4 and 5 are side views and Fig. 6 is a vertical sectional view showing different stages of the clamping operation.

According to our invention we provide a last support herein shown as a post 1, the lower end of which is adapted to be inserted in a socket or hole formed in a work bench or any other convenient supporting means. The post 1 is screw threaded throughout its middle portion for a distance sufficient to permit whatever adjustment may be necessary to enable heels of the widest variation in height to be clamped therein, and a nut in the form of a hand wheel 2 is screwed thereon, said wheel having an upwardly projecting hub portion 3 on the upper end of which a transversely projecting annular flange 4 is formed. A sleeve or carrier 5 is slidably mounted on the post 1 and is transversely grooved at its

lower end, providing a pair of inwardly extending flanges 6, which are adapted to engage the under side of the flange 4, thereby providing a swivel connection with the hand wheel 2 and permitting adjustment of the sleeve or carrier 5 on the post by means of said wheel.

- 10 A loop shaped heel-clamping strap 7 is provided, having parallel end portions in which elongated apertures or slots 8 are formed and extend longitudinally thereof, said slots being adapted to receive projecting pins 9 mounted in the sleeve 5, and said strap being formed of resilient metal and 15 comprising a straight transverse heel top engaging portion 10 at the middle thereof and outwardly bowed side portions or arms connecting the top-engaging portion and the parallel end portions.
- 20 The top end portion of the post 1 is made in the form of an ordinary jack pin, so that, when the lower end is set into the hole or socket provided therefor, a last may be supported on the upper end thereof.
- 25 In using the device, a last with a shoe thereon is placed in position on the post, and, the heel seat having been formed upon the shoe, a heel is set in position thereon. While this is being done the strap 7 will be swung 30 out of the way of the operator, so that he can readily see if the heel is correctly positioned. The heel is then held with one hand, and the strap 7 is swung up over the heel top with the other, so that the middle 35 portion 10 of the strap is directly over some portion of the heel top, and in doing this the strap will be pulled upward, so that the lower ends of the slots will be engaged by the pins 9. When the portion 10 is directly 40 over the heel top, as shown in the dotted line position of Fig. 4, the strap is lowered so that the portion 10 thereof is engaged with the portion of the heel top which can be engaged thereby to the best advantage, as 45 shown in Fig. 5. The heel will then be held in position by pressing down on the strap with one hand while with the other the heel may be readjusted, if necessary, and, when correctly positioned, the operator will rotate 50 the hand wheel 2 with one hand while he holds the strap in position with the other, thereby drawing down the sleeve 5 and causing the pins 9 to engage the lower ends of 55 the slots 8, and then pulling downward upon the strap until its heel engaging portion 10 firmly clamps the heel against the heel seat of the shoe, as shown in Figs. 1 and 6. In practice the sleeve 5 will be drawn down until the bowed side portions are somewhat 60 straightened, as indicated in the dotted position of Fig. 2, so that, in case the heel seat should yield after the clamp has been set aside for the glue to dry, the side portions will spring back towards their normal bowed 65 position and take up the slack thus occa-

sioned. Sufficient pressure of the heel on its seat will thus be retained to insure that it will be securely attached to the shoe.

It is not essential that the top engaging portion 10 of the strap 7 engage the heel top throughout the entire width of the strap, but it may engage at either edge portion and at either the front, back or middle of the heel top lift, according to the pitch of the heel and inclination of the top-lift. By swinging 75 the strap to the desired position of engagement on the heel-top and then pushing it down and positively clamping it, the heel may be clamped to the best advantage without regard to what its particular pitch may be, and the pressure may thus be distributed 80 as uniformly as possible over the entire heel seat.

After the heel has been clamped, the whole device may be removed from the bench and 85 set into a rack, which may be a simple bar having holes to receive the post of the clamp. When the last is to be removed, the wheel 2 is simply screwed up until the strap can be 90 swung back free of the heel.

The above described clamp is of simple 95 and durable construction and is not cumbersome to handle, and with it the operator is enabled to perform the operation of clamping a heel to a shoe with great facility.

We claim:

1. A wood heel clamp comprising a last supporting post, a carrier slidably mounted on the post and having a swiveled screw thread connection therewith, and a clamping 100 strap formed to provide two arms and an intermediate heel-top engaging portion, said arms being pivotally connected at their ends to said carrier and arranged for limited longitudinal movement relatively thereto.

2. A wood heel clamp comprising a last supporting post, a carrier slidably mounted on the post and having means for positively adjusting the same thereon, and a loop shaped strap comprising a pair of approximately parallel arms and an intermediate transverse heel-top engaging portion, said carrier having oppositely projecting pivot pins and said arms having longitudinal slots in their end portions into which said pins 115 extend, to form a pivotal connection therewith and permit limited longitudinal movement relative thereto.

3. A wood heel clamp comprising a last supporting jack, a sleeve slidable on said post and having a swiveled, threaded connection therewith, a loop-shaped strap having a straight intermediate portion adapted to engage the heel top and a pair of arms extending from the ends of said portion, the end portions of said arms having longitudinal slots and said sleeve having pins projecting at opposite sides and entering said slots to provide a pivotal connection therewith constructed and arranged to permit a limit- 125 130

ed amount of sliding movement of said strap relatively to said sleeve.

4. A wood heel clamp comprising a post adapted to support a last at its upper end, 5 a carrier adjustably mounted on said post, a loop shaped clamping strap of resilient metal comprising a pair of arms and an intermediate transverse engaging portion, said arms being pivotally connected at their ends 10 to said carrier and being laterally bowed to provide resilient connection between said carrier and said engaging portion adapted to yield under longitudinal tension and means to force said carrier in a direction 15 to draw said engaging portion against the top of a heel supported on said post.

5. A wood heel clamp comprising a post adapted to support a last at its upper end, a carrier adjustably mounted on said post, a 20 loop shaped clamping strap of resilient metal comprising a pair of arms and an intermediate transverse engaging portion, said arms being pivotally connected at their ends 25 to said carrier and being laterally extended outward from their ends and the ends of 30 said engaging portion to the middle portion thereof, to provide a resilient connection between said carrier and said engaging portion adapted to yield under longitudinal tension and means to force said carrier downwardly on said post.

6. A heel clamp comprising a support for a last, a clamp member for engaging a heel on a shoe on the last, and clamp operating 35 means for moving the clamp member in a direction heightwise of the heel to clamp the heel to the shoe, said means including loosely connected parts constructed and arranged to move relatively to each other to 40 permit a limited amount of free movement of the clamp member in said direction.

7. A heel clamp comprising a support for a last, a resilient clamping member for engaging a heel on a shoe on the last, and clamp operating means for moving the 45 clamping member in a direction heightwise of the heel yieldingly to clamp the heel to the shoe, said means being constructed and arranged to permit a limited amount of movement of the clamping member in said 50 direction relatively to the clamp operating means without affecting the resiliency of the clamping member.

8. A heel clamp comprising a post for supporting a last, a nut threaded on the 55 post, a clamp member for engaging a heel on a shoe on the last, and connections between the clamp member and the nut for moving the clamp member to apply clamp- 60 ing pressure to the heel, said connections being constructed and arranged to permit a limited amount of free movement of the clamp member relatively to the nut in a direction heightwise of the heel.

9. A heel clamp comprising a last engag- 65 ing member and a clamp member for engag- 70 ing a heel applied to a shoe on the last, one of said members being made of resilient metal shaped and arranged to yield a sub-stantial amount under the application of 75 clamping pressure thereto and to react to prevent substantial relieving of said pressure in case the material clamped should subsequently yield, and means connected with one of said members with provision for lost motion between said means and said member for applying clamping pressure to said member.

In testimony whereof, we have signed our names to this specification.

JOSEPH E. ROUSSEAU.
LOUIS O. BRUNELLE.
